UNITED STATES PATENT OFFICE.

LEWIS L. TATUM, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC REGULATOR.

1,186,618.

Specification of Letters Patent. Patented June 13, 1916.

Application filed May 2, 1914. Serial No. 326,924.

To all whom it may concern:

Be it known that I, LEWIS L. TATUM, a citizen of the United States, residing at Milwaukee, in the county of Milwaukee and 5 State of Wisconsin, have invented new and useful Improvements in Electric Regulators, of which the following is a full, clear, concise, and exact description, reference being had to the accompanying drawing, forming a part of this specification.

This invention relates to improvements in electric regulators.

In certain instances, as in the lighting systems of interurban cars where the voltage fluctuates, it is desirable to employ voltage regulators to maintain a substantially constant current in the lighting circuit, although it is unnecessary to provide for a fine degree of regulation.

20 This invention has among its objects to provide a simple and efficient regulator for the aforesaid and other purposes.

A further object is to provide a regulator which will avoid the necessity of differently 25 adjusted relays.

Various other objects and advantages of my invention will hereinafter appear.

The accompanying drawing diagrammatically illustrates the preferred form of the invention, but it should be understood that 30 various modifications may be made therein without departing from the scope of the appended claims.

The regulator illustrated is particularly 35 applicable to lighting systems and is shown as regulating the current of a bank of lamps L.

The regulator consists of a plurality of electro-responsive relays 1, 2, 3, 4, 5, and 6 40 responsive to variations in the lamp current and controlling respectively resistances R', R², R³, R⁴, R⁵ and R⁶ in circuit with the lamps. In practice, any number of these relays may be employed according to the 45 range of current variations to be rectified.

The relays each consist of a normally closed switch with a solenoid S for opening the same. The solenoids of all but the last relay are each provided with two windings 50 s' and s², which act cumulatively. The solenoid of the last relay is provided with but a single winding s'. The windings s' constitute the operating windings and are all set to respond at uniform current values. 55 and to release at uniform current values.

They are, however, so controlled by the relays as to insure against response thereof except in progression. The windings s² constitute holding coils to retain the relays in open position. They are all normally inert 60 and are energized progressively by the relays to render their respective relays less sensitive to current variations or substantially insensitive.

The operation of the regulator will be best 65 understood from a specific description of the circuit arrangement illustrated, which is as follows: Current is supplied to the lamps and to the regulator windings from lines 7 and 8, which, it may be assumed, are connected to any suitable source subjected to variations in voltage. With the relays in normal position current flows from line 7 by conductor 9 through the winding s' of relay 1, thence by conductor 10 through said 75 relay 1, by conductor 11 through relay 2, by conductor 12 through relay 3, by conductor 13 through relay 4, by conductor 14 through relay 5, by conductor 15 through relay 6, by conductor 16 through the lamps 80 L, by conductor 17 to line 8. Under these conditions it will be observed that all of the resistances R', etc., are excluded from circuit and that all of the windings of the relays, with the exception of the winding s' of relay 85 1, are likewise excluded from circuit. This winding, however, is in series with the lamp and is accordingly subjected to variation in the current supplied to the lamps.

Assuming now that there is a fluctuation 90 in voltage causing the lamp current to exceed the value at which winding s' is set to respond, relay 1 will be opened. This inserts in the lamp circuit the resistance R' and the winding s' of relay 2. Under these 95 conditions circuit may be traced from line 7 by conductor 9 through winding s' of switch 1, by conductor 18 through resistance R', by conductor 19 through winding s' of relay 2, by conductor 20 through relay 2 100 and thence through the remaining relays and the lamps, as already traced. Insertion of the resistance R' of course tends to rectify the current of the lamp circuit. If it accomplishes this then no further operation occurs, and if the current decreases abnormally then the winding s' allows the relay 1 to return to normal position and exclude the resistance R' and winding s' of relay 2 from circuit. If, however, the relay 110

- 1 fails to rectify the current variation or if the current increases subsequent to the response of the relay 1, then the winding s' of relay 2 will respond and open the latter. 5 Relay 2 in responding functions similarly to relay 1, as above described, that is, it includes in the lamp circuit the resistance R^2 and the winding s' of relay 3 and remains sensitive to current reduction. Further, 10 upon response it includes in circuit the winding s^2 of relay 1, circuit under these conditions extending from line 7 and conductor 9, through the winding s' of relay 1, through resistance R' and winding s' of relay 2 to conductor 20, as described, thence by conductor 11 through the winding s^2 of relay 1, by conductor 21 through resistance R^2 , by conductor 23 through the winding s' of relay 3, by conductor 24 15 through relay switch 3 and through the remaining relays and the lamps, to line 8, as previously traced. Thus the relay 2 performs a three-fold function: First, it tends to rectify the current increase by the inclusion of the resistance R^2 and remains sensitive to a decrease in current. Second, it renders relay 3 sensitive to further rectify the current increase or to rectify a subsequent current increase. Third, by connecting the winding s^2 of relay 1 in circuit, 20 it increases the holding power of said relay and thus reduces its sensitiveness to negative current variations. Relays 3, 4, 5 and 6 upon responding function similarly to 25 the relays 1 and 2 in inserting their respective resistances in series with the lamps and in connecting the operating winding of the next succeeding relay in circuit. Further, relays 3, 4, 5 and 6 each function similarly to relay 2 in energizing the holding coil s^2 of the next preceding switch. It will thus be seen that upon response of each relay its succeeding relay will be rendered sensitive while all of its preceding relays 30 will be insensitive. On the other hand the dropping out of any relay restores the sensitiveness of its preceding relay and excludes the operating winding of the succeeding relay. Thus, at no time will more than two relays be sensitive, but of these 35 two, one will be sensitive to positive variations of current and the other to negative variations of current thereby providing at all times means to meet both abnormal conditions. It will further be seen that this arrangement enables like adjustment of all 40 of the relays in accordance with the permissible fluctuation of current, and that regulation for systems subject to different ranges of variation may be taken care of by merely varying the number of relays employed.

What I claim as new and desire to secure by Letters Patent is:—

- 65 1. In combination, a translating circuit, a plurality of electro-responsive regulating devices therefor, said devices being substantially uniformly adjusted for operation thereof and having their operating windings responsive to the current of said translating circuit, and means for interlocking said devices for progressive return operations. 70

2. In combination, a translating circuit, a plurality of electro-responsive regulating devices therefor having operating windings responsive to the current in said translating circuit, said devices being substantially uniformly adjusted for operation upon increase in the current of said circuit and means including auxiliary holding windings for certain of said devices to provide for operation of said devices progressively upon reduction in the current of said circuit. 75

3. In combination, a translating circuit, a plurality of regulating resistances therefor, a plurality of controlling switches for said resistances, each of said switches being provided with an operating winding and certain of the same being also provided with auxiliary cumulative windings, said operating windings being of substantially uniform adjustment and responsive to positive current variations in said translating circuit, and inter-connections whereby the auxiliary windings are included in and excluded from circuit sequentially to provide for operation of said switches progressively under negative current variations. 80

4. In combination, a translating circuit, a plurality of electro-responsive regulating devices therefor having their windings subjected to the electrical variations in said circuit and being substantially uniformly adjusted for control of said devices and inter-connections for said devices whereby not 100 more than two of the same are sensitive at any time and whereby such two devices are sensitive to positive and negative variations respectively. 105

5. In a regulator, in combination, a plurality of progressively acting electromagnetic switches of substantially uniform adjustment for operation thereof, each of said switches being provided with an operating winding and certain of the same being each 110 provided with a cumulative auxiliary winding, inter-connections whereby the operating windings of all but the first switch are each controlled by a preceding switch and inter-connections whereby the auxiliary windings 115 of all but the last switch are each controlled by a succeeding switch, to provide for progressive operation of said switches in response to both positive and negative variations in the current to which their windings 120 are subjected. 125

6. In a regulator, in combination, a plurality of electro-responsive regulating devices, all but one normally insensitive, and interconnections for said devices whereby 130

each is rendered sensitive to positive electrical variations upon response of a preceding device and is rendered substantially insensitive to negative variations upon response of a succeeding device.

7. In a regulator, in combination, a plurality of electro-responsive regulating devices of substantially uniform sensitiveness to positive and negative electrical variations, and means insuring response of said devices progressively and automatically reducing the sensitiveness of each to negative variations upon response of its next succeeding device.

15 8. In a regulator, a plurality of electro-responsive regulating devices interlocked for progressive response thereof, and holding coils for a number of said devices, each of said coils being energized upon response 20 of the device succeeding its respective device.

9. In a regulator, in combination, a plurality of electro-responsive regulating devices each being provided with an operating 25 winding and a number of the same being each provided with an auxiliary winding acting cumulatively with its operating winding, and inter-connections between said devices whereby the response of each except 30 the first is dependent upon the response of its preceding device and whereby each of the remaining devices upon responding effects the energization of the auxiliary winding of its preceding device.

35 10. In a regulator, in combination, a plurality of progressively operating switches each provided with an operating winding and each but the last being further provided with an auxiliary cumulative winding, all 40 of said windings being adapted for series connection but all but the operating wind-

ing of the first switch being normally excluded from circuit, and interconnections between said switches whereby the first upon responding includes in circuit the operating 45 winding of the next succeeding switch and whereby each remaining switch upon responding includes in circuit the auxiliary winding of its next preceding switch and the operating winding of its next succeeding 50 switch.

11. In combination, a translating circuit, a plurality of resistances for series connection therein, a plurality of progressively operating switches for controlling said resistances and normally disconnecting all of the same from circuit, each of said switches being provided with an operating winding and each but the last being further provided with an auxiliary cumulative winding, all 55 of said windings being adapted for series connection in said translating circuit but only the operating winding of the first switch being normally included in circuit, and interconnections between said switches 60 whereby the first upon responding includes in said translating circuit one of said resistances and the operating winding of the next succeeding switch and whereby each of the remaining switches upon responding includes in the translating circuit another of said resistances, the auxiliary winding of its next preceding switch and the operating winding of its next succeeding switch. 70

In witness whereof, I have hereunto subscribed my name in the presence of two witnesses. 75
